UNITED STATES PATENT OFFICE.

EDWARD G. CARR, OF CHICAGO, ILLINOIS.

CONCRETE-ROAD MACHINE.

Application filed December 29, 1921. Serial No. 525,572.

This invention relates to concrete road machines and the object of the invention is to improve the construction and operation of concrete road machines in the manner to be hereinafter described and claimed.

Referring to the drawings which accompany this specification and form a part hereof, which drawings illustrate an embodiment of this invention, and on which drawings the same reference characters are employed to designate the same parts wherever they may appear in each of the several views, Fig. 1 is a plan view of a concrete road machine; Fig. 2 is an elevation of the front end of the machine, parts being omitted; Fig. 3 is a vertical, longitudinal section on the line 3—3 on Fig. 1, looking in the direction indicated by the arrows; Fig. 4 is an elevation of parts of the machine, parts being shown in section; Fig. 5 is a cross section of parts of the machine on the line 5—5 on Fig. 6, looking in the direction indicated by the arrows; and Fig. 6 is a cross section on the line 6—6 on Fig. 4, looking in the direction indicated by the arrows.

Referring to the drawings, the reference numeral 1 designates a frame which may be constructed in any suitable or preferred manner and which is supported by wheels 2 upon tracks or forms 3. The frame 1 supports a motor 4 which may be of any suitable or preferred construction, the motor 4 illustrated by the drawings being an ordinary form of gasoline or internal combustion motor or engine, to the shaft 5 of which is rigidly secured a sprocket wheel 6. A countershaft 7 is suitably journaled on the frame 1 and has rigidly secured thereto a sprocket wheel 8, a gear 9 and a second sprocket wheel 10. The sprocket wheels 6 and 8 are connected by a straight sprocket chain 11. A driving shaft 12 is journaled on the frame 1 and is provided with a bevel gear 13, a spiral gear 14, a gear 15, and a sprocket wheel 16, which are all loose thereon but are individually restrained from longitudinal movements with respect to the driving shaft 12. The sprocket wheels 10 and 16 are connected by a straight sprocket chain 17 and the spiral gear 14 is provided with a clutch member 18, the gear 15 is provided with a clutch member 19, and the sprocket wheel 16 is provided with a clutch member 20. A clutch member 21 is splined, or otherwise suitably secured to the driving shaft 12 so as to be rotated thereby while

being free to be moved longitudinally thereof to clutch the spiral gear 14 to the driving shaft 12 or to unclutch it therefrom. A clutch 22 is provided with a clutch member 23 to co-act with the clutch member 19 on the gear 15, and a clutch member 24 to co-act with the clutch member 20 on the sprocket wheel 16, and this clutch 22 is splined to the driving shaft 12, or otherwise suitably secured thereto, so as to rotate the same, while being free to be moved longitudinally thereof, and it will be readily seen that a movement of the clutch 22 to the right, see Fig. 1 of the drawings, will clutch the gear 15 to the driving shaft 12, while a movement of the clutch 22 to the left, will clutch the sprocket wheel 16 to the driving shaft 12. The longitudinal movement of the clutch 22 is sufficient so that it can occupy a neutral or stop position without engaging with either the clutch member 19 or the clutch member 20. The driving shaft 12 is illustrated as provided with universal joints 25 and has at its ends worms which mesh with worm wheels which are rigidly secured to longitudinal shafts 26 and 27. The longitudinal shafts 26 and 27 are provided with worms which mesh with worm wheels secured to the wheels 2, and it will be readily seen that, with the construction thus far described, the machine can be propelled forward or backward, or stopped, by properly positioning the clutch 22 while the motor 4 is in operation.

A flexible float or finisher 28 is secured to a U-shaped frame 29 which is slidably and rotatably supported by brackets 30 and 31 extending from the frame 1. The U-shaped frame 29, and the float or finisher 28, is reciprocated transversely of the road, when turned down upon the road in operative positions, by means of a pin 32 which engages with a slide 33 adapted to be reciprocated by a connecting-rod 34 and a crank 35 secured to the longitudinal shaft 26. The U-shaped frame 29, and the float or finisher 28, may be turned up to non-operative positions and the pin 32 disengaged from the slide 33 by such turning operation.

A spreading templet 36 is slidably supported for reciprocation upon a transverse rod 37 which is secured to the angles of bell-crank levers 38 and 39. The short arms of the bell-crank levers 38 and 39 are provided with axle-pins 40 and 41 for wheels 42 and 43 to form an independent supporting frame

for the spreading templet 36. The spreading templet 36 may be pushed forward, or propelled backward, by being connected to the frame 1 by links 44 which may include in their connections vertical pins 45 and horizontal pins 46 to allow for universal play for running over small obstructions, track joints for example, and for rounding curves. The bell-crank levers 38 and 39 serve as lifting and lowering means for the spreading templet 36 and they are located adjacent notched sectors 47 and 48 adapted to be engaged by detents 49 and 50, which are illustrated as spring pressed and manipulated by grips 51 and 52. A ring or link 53 can be slipped over one grip and its bell-crank lever so that both ends of the spreading templet 36 can be raised or lowered simultaneously from either side of the machine. The notched sectors 47 and 48 can be loosely supported upon the transverse rod 37 and kept from turning by links 54 and 55 connected to the sectors and to the frame 1 by jointed connections which will permit of the movements permitted by the links 44.

A clutch 56, splined to the driving shaft 12, can be operated to clutch the bevel gear 13 to the driving shaft 12 or unclutch it therefrom. The bevel gear 13 meshes with a bevel gear 57 on a shaft 58. The shaft 58 is supported by a bracket 59 at one end, is supplied with universal joints 60, one of which is also a sliding joint, and its other end is supported on a housing 61 which is secured to the spreading templet 36. The shaft 58 has secured thereto, within the housing 61, an eccentric weight 62 and a spur gear 63. A shaft 64, also journaled in the housing 61, has a like eccentric weight 64 and a like spur gear 65 which is in mesh with the spur gear 63. The eccentric weights 62 and 64 are so set on the shafts that they both extend in the same direction horizontally whereby, as they approach their horizontal positions, they will thrust the spreading templet 36 longitudinally but will balance each other, when one is moving up and the other is moving down, so as not to produce vertical thrusts or movements of the spreading templet. The springs 66 and 67 act as shock absorbers for the longitudinal thrusts of the spreading templet 36, whenever the concrete does not offer sufficient resistance to absorb the kinetic energy of the thrusts produced by the eccentric weights 62 and 64, and also tend to center the spreading templet.

Two tampers 68 and 69 are illustrated by the drawings as placed parallel and arranged in a non-parallel relation with respect to the spreading templet 36 and the float or finisher 28. A shaft 70 extends parallel with the tampers 68 and 69 and has a spiral gear 71 fast thereon to rotate the shaft 70 when the spiral gear 14 is clutched to the driving

shaft 12. The shaft 70 is provided with universal and sliding joints 72 and has bevel gears 73 and 74 which are connected with like sides of bevel gears 75 and 76 secured to shafts 77 and 78, so as to rotate shafts 77 and 78 in the same direction. The shafts 77 and 78 are each provided with oppositely disposed cranks 79 and 80, that is cranks on the shafts 180 degrees apart, and the cranks for a single tamper extend in the same direction so that the motion of any point in a tamper would be in a circle. The tampers are provided with stiff springs 81 and boxes 82 secured to the springs 81 are journal boxes to suspend the tampers from the cranks 79 and 80 at each end. The shafts 77 and 78 are hung from links 83 which are pivoted to bell-crank levers 84 and 85 which are pivoted to the frame 1 so that the tampers 68 and 69 can be raised away from or lowered towards the concrete. The different positions which may be assumed by the shafts 77 and 78 is the reason for the universal and sliding joints in the shaft 70. The bearings for the shaft 70 preclude longitudinal movements of the tampers 68 and 69, except, of course, as such longitudinal movements are effected by the rotation of the cranks 79 and 80.

The bell-crank levers 84 and 85 may be connected by a link 86 for simultaneous movement so that both ends of the tampers 68 and 69 may be raised or lowered simultaneously. One of the bell-crank levers, 84 for example, may have a long arm to serve as an operating lever and be provided with a spring pressed detent 87 and a grip 88. The detent 87 can be engaged with a notch in a notched sector 89 secured to the frame of the machine so that the tampers can be held in different vertical positions.

The operation of the machine will be obvious from the foregoing description as to its propulsion, the operation of the motion transmitting mechanism, the clutches or clutch members, the spreading templet and the float or finisher, but the principle of operation of the tampers requires further explanation. A point in a tamper moves in a vertical circle in the plane of the tamper, except as the springs 81 may be deflected or bent. The motor 4 turns over in such a direction that, when the machine is moving forward, spreading templet leading, the tampers are moving at the bottoms of their circular motions towards their leading ends, or towards the observer's left hand when looking at Fig. 1 of the drawings. When the direction of motion of the machine is reversed, it will be obvious that the direction of movement of the tampers at the bottoms of their circular motions will also be towards their leading ends. In other words, the longitudinal movements of the tampers, when in contact with the concrete, is always in the

general direction of movement of the machine so that there is a longitudinal rubbing action of the tampers upon the concrete as well as the forward movements of the tampers as a whole due to the forward movement of the machine and, these movements being in the same general direction, the tendency to remove excess material from high places and fill up depressions is intensified in addition to the vertical effect of the tampers.

The non-parallel relation of the members which work upon the concrete is of advantage for the following reasons. The straight-across-the-road spreading templet is liable to leave waves especially at the joints of tracks when care has not been exercised to properly support and even up the joints. If the tamper, or tampers, were parallel with such waves, the wave form would remain to a greater or less extent, depending upon the consistency of the concrete. Such waves in a road are called "corduroy" and are highly objectionable as both wheels of a vehicle strike them at the same time. By arranging a tamper obliquely to the spreading templet, the corduroy effect can be practically eliminated by careful manipulation of the machine, and, if the machine be carelessly manipulated, the corduroy effects may be transformed into waves running diagonally across the road and will be less objectionable because both wheels of a vehicle will not hit the same corduroy at the same time. While the float or finisher 28 is not capable of any very severe action on the concrete, it can and will smooth the cement mortar fairly well even though it be left pretty rough by the tampers, and, as its motion is obliquely across the waves, it can more effectively produce a uniformly smooth surface than as though it reciprocated in parallelism with the waves.

The reference numeral 90, on Fig. 3 of the drawings, designates a shifting lever for the clutch 22.

45 What is claimed is:

1. The combination in a concrete road machine, of a spreading templet, and a vertically reciprocatable tamper arranged in non-parallel relation to each other, and means for reciprocating the tamper vertically.
2. The combination in a concrete road machine, of a vertically reciprocatable tamper, a float following the tamper and arranged in non-parallel relation to the tamper, and means for reciprocating the tamper vertically.
3. The combination in a concrete road machine, of a spreading templet, and a float arranged substantially parallel with each other, a tamper between the spreading templet and the float and arranged at an angle

with respect to them, and means for operating the tamper.

4. In a concrete road machine, the combination of a tamper, of means for moving the tamper both vertically and longitudinally of itself, said means being adapted to move the tamper longitudinally of itself while in contact with the concrete.

5. In a concrete road machine, the combination with a tamper, of means for moving any point in the tamper in a circle in the vertical plane of the tamper.

6. In a concrete road machine, the combination with a frame, of a tamper carried thereby and movable therewith, means to propel the frame, and means for operating the tamper vertically and to cause the tamper to be moved longitudinally of itself, in a direction at an angle to the movement of the frame while the tamper is in contact with the concrete.

7. In a concrete road machine, the combination with a frame adapted to be propelled in opposite directions, of a tamper carried by the frame and so disposed with respect to the frame that one end of the tamper will be in advance of the other end of the tamper whatever may be the direction of movement of the frame, means for elevating and depressing the tamper and moving it longitudinally of itself so that it will be moved longitudinally of itself while in contact with the concrete, and means for changing the direction of the longitudinal movement of the tamper, while in contact with the concrete, when the direction of movement of the frame is changed, so that the movement of the tamper, longitudinally of itself, while in contact with the concrete, will be in the same general direction as the movement of the frame.

8. In a concrete road machine, the combination with a movable frame, of an obliquely arranged vertically movable tamper carried thereby, means to propel the frame in opposite directions, means to move the tamper longitudinally of itself when in contact with the concrete, and adapted to change the longitudinal direction of movement of the tamper, while in contact with the concrete, when the direction of movement of the frame is changed.

9. In a concrete road machine, the combination with a frame, of means for propelling the frame, and a spreading templet supported independently of the frame but adapted to be propelled thereby.

In witness whereof I hereto affix my signature.

EDWARD G. CARR.
